UNITED STATES PATENT OFFICE.

WILLIAM D. SNOW, OF PHILADELPHIA, PENNSYLVANIA.

PRINTING-BLOCK-ADJUSTING MACHINE.

SPECIFICATION forming part of Letters Patent No. 770,543, dated September 20, 1904.

Application filed June 2, 1904. Serial No. 210,816. (No model.)

To all whom it may concern:

Be it known that I, WILLIAM D. SNOW, of the city and county of Philadelphia and State of Pennsylvania, have invented an Improvement 5 in Printing-Block-Adjusting Machines, of which the following is a specification.

My invention has reference to machines for adjusting printing-blocks to heads of machines for printing linoleum, oil-cloth, &c.; and it 10 consists of certain improvements, which are fully set forth in the following specification and shown in the accompanying drawings, which form a part thereof.

Heretofore great difficulty has been experienced in adjusting the printing-blocks upon the heads of the printing-machines employed in printing linoleum and oil-cloth, with the result that a very considerable increase in cost of printing has been incurred from loss of 15 time both of the workmen and in the actual use of the machine in printing. As these machines are very costly and occupy large buildings, the loss in the use of the investment during such periods becomes a very grave matter 20 to the manufacturer. It is also evident that as the change and adjustment of the printing-blocks are necessary for each special pattern it would hardly pay to print small orders, and because of the loss of the use of the machine 25 during the tedious changing and adjusting of the numerous printing-blocks the cost of printing the fabric is necessarily higher than it should be.

The object of my invention is to overcome 30 the above objections by providing a special machine upon which the printing-blocks may be adjusted upon a duplicate set of heads during the normal operation of the printing-machine in its work upon another pattern, the 35 said heads and attached blocks being quickly substituted for the heads and blocks in the machine. In this way the printing-machine is actually out of use for a few minutes only, and hence the numerous employees required to operate it are kept employed. A great advantage is apparent from the fact that considerably less printing apparatus is necessary for a given output, thereby creating a great saving in investment in machinery, buildings, and 40 labor.

In embodying my invention into practice I

provide a support for the head of the printing-machine and combine therewith a track-way and a test-carriage adapted to be moved upon the trackway and across the printing-blocks on the head, whereby the adjustment of the several printing-blocks may be accurately adjusted and secured to the head, so that when transferred to the printing-machine they shall be in exact position for perfect 55 printing.

My invention also comprehends details of construction, which, together with the above features, will be better understood by reference to the drawings, in which—

Figure 1 is a plan view of my improved machine. Fig. 2 is a side elevation of same. Fig. 3 is a cross-section of a portion of same on line 3 3 of Fig. 1, and Fig. 4 is a cross-section on line 4 4 of Fig. 1.

A is the main frame of the machine and has the guide-rails B B arranged at a distance apart.

C C are two standards extending upward above the rails and support the printing-block head E, which is provided with downwardly-extending ends e, having transverse holes, said ends fitting into the slotted upper ends c of the standards and secured therein by pins F, which are the means of attachment of the 75 head to the standards and also for bringing it into proper relative adjustment with the rails B B.

The head E may be made in any suitable manner, that shown being formed of two girders connected by cast-iron spacing-pieces. To the under side of the head are arranged a series of printing-block-supporting frames G, which are clamped to the lower flanges of the head by clamps H, whereby they may be adjusted along the length of the head and transversely to the tracks. To these supporting-frames G are secured the printing-blocks I, which are made of wood or other suitable material and secured in place by screws. For 80 accurate printing it becomes necessary to have the lower faces or printing-surfaces of the blocks in perfect alinement in the same plane, and this is secured by either interposing spacing layers between the block and supporting-frames or by rubbing down the printing-face 85 of the block, as desired.

J is a transversely-arranged carriage and is provided with supporting-wheels K, which run upon the tracks B. This carriage is furnished with a transverse color-roller L, which 5 is adapted to apply color to the under surfaces of the printing-blocks I. It is desirable to cause said rollers L to rotate during the travel of the carriage, and to do this I provide a system of gearing adapted to make the 10 color-applying roller rotate inversely with a surface speed equal to the travel of the carriage, so as to prevent any sliding motion over the printing-block. In this way the apparatus conforms exactly to the conditions of 15 the printing-machine and insures all adjustments being made in accordance with the actual requirements of the printing-machine itself.

The gearing mentioned above consists of a 20 spur-gear M on the end of the roller L, a gear O on the carriage and meshing with a rack N on the main frame parallel to the rail B, and intermediate gears P P, connecting the gears O and M and causing the former to 25 rotate in the proper direction. The gears P P are journaled in a frame R, pivoted concentrically with the axis of the roller L, so as to maintain gear connection with gear M, while having capacity for being put into or 30 out of mesh with gear O. Any other form of gearing may be employed in lieu of that shown, if so desired, or gearing may be dispensed with altogether, and the color-applying device may be made in any other suitable 35 manner.

The gear O is secured to the end of the axles P of the carriage, and a similar gear on the opposite end of said shaft meshing with a second rack N' insures the travel of the carriage being uniform at both sides of the machine. The other axle may also be provided 40 with gears O², meshing with the same racks N N', if so desired.

When the various parts of the apparatus 45 are in the relation shown, the strains due to gravity will put them into the same condition which will normally be had in the printing-machine, and consequently such adjustments as may be made to the printing-blocks I upon 50 their supporting-frames and head will exactly meet the requirements of the printing-machine.

It will now be seen that while the printing-machine is in operation on one pattern the 55 printing-blocks of another pattern may be adjusted and secured in position upon a duplicate set of heads E, (one for each color,) so that all that is necessary is to remove one set of heads and substitute another with the newly-60 adjusted printing-blocks upon them. In this manner the printing-machine is out of actual operation only a very short period of time, and the great losses heretofore experienced are thereby overcome.

65 To facilitate the handling of the heads E,

they are provided with the trunnions c' on their ends, which may be received in hooks S of a traveling crane. When the heads are to be removed, the transverse pins F are driven out to release the head from the standards C. 70

If desired, the standards may be formed with an upper jointed portion C², hinged to the lower part at C' and normally locked in upright position by clamp C³. When the clamp is released, the head E may be turned 75 over to examine the application of color to the under surfaces of the blocks I and to ascertain what further adjustment may be necessary.

In the machine as shown the color is applied to the roller L with a pad by hand; but it is evident that it may be applied in any other manner preferred. 80

The reciprocating movement of the carriage J is by hand; but I do not confine myself to 85 hand adjustment.

It is evident that while I have arranged the head E above and the color-roller below, as in the case of the normal construction of printing-machines, I do not limit myself to this arrangement, as the parts may equally be inverted, while maintaining the same relative 90 conditions.

While I prefer the construction shown, I do not confine myself to the details, as they 95 may be modified without departing from the spirit of the invention.

Having now described my invention, what I claim as new, and desire to secure by Letters Patent, is— 100

1. In a machine for adjusting printing-blocks on heads to be used on printing-machines, the combination of a guideway, a support for the head for holding it and its attached printing-blocks in fixed relation against vertical movement to the guideway, and a traveling carriage adapted to move on the guideway and provided with a color-carrying surface to apply color to the printing-blocks to indicate 105 the extent of the adjustment required. 110

2. In a machine for adjusting printing-blocks on heads to be used on printing-machines, the combination of a guideway having racks, a support for the head for holding it and its attached printing-blocks in fixed relation against vertical movement to the guideway, and a traveling carriage adapted to move on the guideway and provided with gearing meshing with the racks to insure both ends of the carriage moving at the same speed, and a 115 color-carrying surface carried by the carriage to apply color to the printing-blocks to indicate the extent of the adjustment required. 120

3. In a machine for adjusting printing-blocks on heads to be used on printing-machines, the combination of a guideway, a support for the head for holding it and its attached printing-blocks in fixed relation against vertical movement to the guideway, a traveling carriage adapted to move on the guideway, 125 130

means on the carriage and guideway for causing the carriage to move at same speed at both ends, and a color-carrying roller to apply color to the printing-blocks to indicate the extent of 5 the adjustment required.

4. In a machine for adjusting printing-blocks on heads to be used on printing-machines, the combination of a guideway, a support for the head for holding it and its attached 10 printing-blocks in fixed relation against vertical movement to the guideway, a traveling carriage adapted to move on the guideway, means for causing the carriage to move at same speed at both ends, consisting of racks 15 on the guideway and connected gearing on the carriage, a color-carrying roller to apply color to the printing-blocks to indicate the extent of the adjustment required, and means to rotate the color-carrying roller inversely to the 20 direction of movement of the carriage.

5. In a machine for adjusting printing-blocks on heads to be used on printing-machines, the combination of a guideway, a support for the head for holding it and its attached 25 printing-blocks in fixed relation against vertical movement to the guideway, a traveling carriage adapted to move on the guideway, means for causing the carriage to move at same speed at both ends consisting of racks 30 on the guideway and connected gearing on the carriage, a color-carrying roller to apply color to the printing-blocks to indicate the extent of the adjustment required, and means to rotate the color-carrying roller inversely to the 35 direction of movement of the carriage consisting of a gear on the roller and connecting adjustable gearing between said gear and the gear of the carriage.

6. In a machine for adjusting printing-blocks on heads to be used on printing-machines, the combination of a guideway, a support for the head for holding it and its attached printing-blocks in fixed relation to the guideway, a traveling carriage adapted to 40 move on the guideway, means for causing the carriage to move at same speed at both ends consisting of racks on the guideway and connected gearing on the carriage, a color-carrying roller to apply color to the printing-blocks 45 to indicate the extent of the adjustment required, means to rotate the color-carrying roller inversely to the direction of movement of the carriage consisting of a gear on the roller and connecting-gearing between said 50 gear and the gear of the carriage, and means for putting said connecting-gearing into or out of operation.

7. In a machine for adjusting printing-blocks on heads to be used on printing-machines, the combination of a guideway, a sup- 55

port for the head for holding it and its attached printing-blocks in fixed relation against vertical movement to the guideway consisting of fixed standards having recessed ends into which lugs on the head fit, removable trans- 65 verse pins passing through the lugs to detachably hold the head at a fixed distance from the guideway, and a removable carriage for the guideway having a part to gage the position of the printing-blocks on the head. 70

8. In a machine for adjusting printing-blocks on heads to be used on printing-machines, the combination of a guideway, a support for the head for holding it and its attached printing-blocks in fixed relation against 75 vertical movement to the guideway consisting of fixed standards provided with hinged upper portions having recessed upper ends into which lugs on the head fit, removable transverse pins passing through the lugs to detachably hold the head at a fixed distance above the guideway, and a movable carriage for the guideway having a part to gage the position of the printing-blocks on the head. 80

9. In a machine for adjusting printing-blocks on heads to be used on printing-machines, the combination of a guideway, a support for the head for holding it and its attached printing-blocks in fixed relation to the guideway consisting of jointed standards for 90 permitting the head and its printing-blocks to be turned over for inspection, and a movable carriage for the guideway having a part to gage the position of the printing-blocks on the head. 95

10. In a machine for adjusting printing-blocks on heads to be used on printing-machines, the combination of a guideway, a support for the head for holding it and its attached printing-blocks in fixed relation against 100 vertical movement to the guideway, and a movable gage device movable over the guideway having a transverse part to gage the position of the several printing-blocks on the head. 105

11. In a machine for adjusting printing-blocks on heads to be used on printing-machines, a head having a series of printing-blocks, and a gage device for gaging the position of the printing-blocks on the head and having a transverse relative movement with respect to the head, and supports for the head and gage device for holding said parts at a definite fixed distance apart. 110

In testimony of which invention I hereunto 115 set my hand.
